(57) **CLAIM**

The ornamental design for a musical instrument, as shown and described.

DESCRIPTION

FIG. 1 is a front perspective view of a musical instrument showing our new design;

FIG. 2 is a front view thereof;

FIG. 3 is a back view thereof;

FIG. 4 is a side view thereof;

FIG. 5 is the side view opposite to FIG. 4;

FIG. 6 is a top view thereof; and,

FIG. 7 is a bottom view thereof.

It is understood that the appearance within the boundaries of the various unshaded circular and rectangular apertures forms no part of the claimed design.
